UNITED STATES PATENT OFFICE

ARO M. HARVEY, OF KANSAS CITY, MISSOURI

IRONING BOARD

Application filed August 30, 1928. Serial No. 302,985.

My invention relates to pressing tables, and more particularly to ironing boards used in laundries and dry cleaning shops, the principal objects of the invention being to support a secondary ironing board in rest position spaced longitudinally from a primary ironing board and in parallel relation therewith, to provide for moving the secondary board into and out of supported relation with the primary board, and to lower a sleeve board into supported engagement with a primary board coincidently with movement of the sleeve board into alignment with the primary board.

15 A further object is to provide apparatus whereby a plurality of interchangeable ironing boards may be supported in convenient relation with a work shelf and a selected board may be moved into supported relation 20 with the shelf.

In laundries and similar establishments where many ironers are employed, several primary ironing boards may be provided, and the storing of the secondary ironing 25 boards to economize space and yet have such boards easily available for use of any operator is a serious problem. Further objects of my invention therefore are to minimize the space requirement of a secondary board 30 when not in use, to prevent interference of a secondary board when idle or being moved with adjacent workers, and to facilitate the positioning of a secondary board.

In accomplishing these and other objects 35 of the invention, I have provided improved details of structure, the preferred forms of which are illustrated in the accompanying drawings, wherein:

40 Fig. 1 is a perspective view of the device illustrating a pressing table provided with a selected sleeve board and supported from a primary ironing board.

Fig. 2 is a plan view of the device in the 45 position shown in Fig. 1, but with the sleeve board removed, and the position of the base with reference to the primary board reversed.

Fig. 3 is a perspective view of the device 50 illustrating the pressing table in retracted

position spaced horizontally and vertically from the primary ironing board.

Fig. 4 is a central vertical sectional view of the pivotal connection between the base member of a pressing table and a bracket 55 arm.

Fig. 5 is a side elevation of a rule joint in the bracket arm.

Fig. 6 is an elevation of the pivotal mounting of the bracket arm in the bracket illustrating the cooperating cam portions of the two members, the bracket being shown fragmentarily and in vertical central section.

Fig. 7 is a perspective view of the arm-receiving portion of the bracket. 65

Referring in detail to the drawings:

1 designates a work shelf comprising preferably a relatively large primary ironing board suitably supported from a floor by means not shown. A pressing table 2 comprises an elongated base 3, a bracket 4 secured to the base and having a rearwardly projecting lug 5, and a secondary ironing board 6 such as a sleeve board mounted on the bracket and having a flange 7 adjacent its rear end provided with an opening 8 to receive said lug for latching the sleeve board to the bracket. 70

The pressing table 2 is normally supported in rest position in parallel spaced relation 80 with the shelf 1 by a bracket 9 supported in fixed relation with the shelf and preferably mounted on the shelf, and a jointed bracket arm 10 pivotally connected to the base 3, whereby the table may be moved into position for direct support from the shelf as presently described. 85

The bracket 9 includes an upwardly and outwardly extending bearing flange 11 reinforced by ribs 12 and having a pin-receiving opening 13, and a cam boss 14 on the upper face 15 of the flange having a taper portion 16 and a shoulder 17. 90

The jointed bracket arm includes a member 18 secured to a socket 19 pivotally mounted by a pin 20 on a disk 21 secured to the base 3 adjacent the center thereof, and a member 22 having one end connected to the first member by a rule joint 23 and the other end secured to a socket 24 having a cam por- 95

95

100

tion 25 including a taper portion 26 and a shoulder 27 for cooperation with the cam of the bracket, and pivotally connected to the bracket by a pin 28 extending in the opening 13.

The pin 28 extends through the flange 11 and a spring 29 seated in a recess 30 of the flange is anchored by the bracket flange and bears against a washer 31 on the pin to latch 10 the socket member in retracted or functioning position of the pressing table and accelerate the movement of the socket member cam over the flange cam.

The disk 21 secured to the base 3 has a boss 15 32 supporting the socket 19 in spaced relation with the base, and over which the face 33 of the socket member 19 is rotatable, and a recess 34 to receive the head 35 of the pivot pin 20. The rule joint includes mated portions 36 and 37 on the ends of the arm members pivotally connected by a pin 38, and having cooperating shoulder-like flanges 39 and 40 for limiting the relative movement of the arm members.

25 A plurality of secondary boards 41 and 42 similar to the board 6 may be provided for replacing the board 6 on the base, and are supported when not in service on a rack 43 comprising a post anchored in a socket 44 of the bracket 9 and having radial hooks 45 adjacent its upper end adapted to enter the openings 8 and then engage the flanges 7 of the boards, whereby the boards will be supported in substantially vertical position.

35 A sponge-holder 46 comprising a cup-shaped wire frame has an arm 47 bent around the post for frictional engagement therewith to support the frame from the post, and a cup 48 is similarly supported below the sponge 40 frame by a wire loop 49 embracing the post, whereby a sponge 50 normally lying on the frame 46 in spaced relation with water carried by the cup 48, may be pressed into the water to absorb a portion thereof for use in 45 moistening articles to be ironed on the boards.

In using apparatus constructed as described, the major proportion of ironing operations is performed on the primary ironing board. The secondary boards are conveniently available, and are securely supported in such positions that they do not interfere with the movements of the operator about his primary board, or with adjacent operators. The pressing table may be swung into adjustment with the primary board without extending forwardly further than the length of the table from the bracket to clear the bracket. The maximum lateral extension of the pressing table and bracket arms from the primary ironing board comprises the arc described by the arm member 22, since the base and the sleeve board may be moved longitudinally from retracted position by reason of the jointed and doubly pivoted character of the bracket arm.

While the pressing table is being moved laterally to alignment with the primary ironing board, the cam of the bracket arm socket 24 slides downwardly over the cam of the bracket flange, whereby the base is deposited 70 on the primary board and is supported directly therefrom.

When the pressing table is to be retracted, the operator may move it toward retracted position to cause the reverse cam action to 75 that previously described, whereby the table is lifted while being rotated and when swung into rest position will be supported in horizontally and vertically spaced relation with the primary board, and rearwardly therefrom.

The adaptation of the supplemental boards for mounting on the base and support of the pressing table provide means for storing the boards on the bracket-supported rack, since 85 the rear-end apertured flanges of the boards when engaged with the hooks will cause the boards to hang in substantially vertical position with their lower ends inclined towards the post.

90 The shoulder flanges of the rule joint limit the rotation of one bracket arm member in relation to the other, to prevent swinging of the pressing table and outer bracket arm rearwardly of the inner bracket arm.

95 The pivotal mounting of the outer bracket arm on the base provides not only for the swinging movement into and out of retracted position, but for rotating the pressing table to position either the narrow or the wide end 100 of the sleeve board adjacent the rear end of the primary board.

What I claim and desire to secure by Letters Patent is:

1. In a device of the character described, 105 a support, an ironing board, and means supporting the ironing board from the support including a bracket fixed to the support, a bracket arm connected to the board, and a bracket arm having a rule joint connected with the first named arm and pivoted in the bracket.

110 2. In combination with a support, an ironing board, and a bracket supported in fixed relation with the support, means for moving the ironing board into and out of engagement with the support including a cam on the support, and a jointed bracket arm connected to the ironing board and horizontally pivotally mounted on the bracket, and adapted upon horizontal movement to engage the cam for lifting the ironing board from the support during horizontal movement of the ironing board.

115 3. In apparatus of the character described, 125 a support, a sleeve board, and a bracket supported in fixed relation with the support, a cam on the bracket, and a bracket arm including a member pivotally mounted on the bracket for movement on the cam and a mem- 130

ber pivoted to the first named member and pivotally engaged with the sleeve board for enabling the sleeve board to be moved into and out of supported aligned relation with the support.

5 4. In combination with a support and a sleeve board, a bracket mounted on the support, a bracket arm having a pivot pin pivotally mounted in the bracket, means connecting the bracket arm with the sleeve board, a cam on said bracket supporting the arm, and a spring bearing oppositely against the bracket and the pin.

10 5. In apparatus of the character described, a support, an arm pivotally mounted on the support for lateral swinging with reference to the support, a sleeve board supported by the arm, and means for moving the board vertically toward the support upon swinging of the board into registry therewith including a cam member on the arm and a spring engaged 20 with the arm and anchored on the support.

In testimony whereof I affix my signature.
ARO M. HARVEY.
